UNITED STATES PATENT OFFICE

145,520

DESIGN FOR A TABLE OR SIMILAR ARTICLE

Claybourne W. Hart and Amplis O. Hart,
Chicago, Ill.

Application December 15, 1945, Serial No. 124,768

Term of patent 7 years

(Cl. D33—14)

To all whom it may concern:

Be it known that we, Claybourne W. Hart and Amplis O. Hart, both citizens of the United States, residing at Chicago, in the county of Cook and State of Illinois, have invented a new, original, and ornamental Design for a Table or Similar Article, of which the following is a specification, reference being had to the accompanying drawing, forming part thereof.

We claim:

The ornamental design for a table or similar article, as shown.

CLAYBOURNE W. HART.
AMPLIS O. HART.
